Primary Examiner — Garth Rademaker*Assistant Examiner* — Lilyana Bekic(74) *Attorney, Agent, or Firm* — Finnegan, Henderson, Farabow, Garrett & Dunner LLP(57) **CLAIM**

The ornamental design for a syringe pump housing, as shown and described.

DESCRIPTION

FIG. 1 is a front bottom right perspective view of a syringe pump housing showing my new design; FIG. 2 is a front elevation view thereof; FIG. 3 is a rear elevation view thereof; FIG. 4 is a top plan view thereof; FIG. 5 is a bottom plan view thereof; FIG. 6 is a left side view thereof; and, FIG. 7 is a right side view thereof.

The broken lines shown in the drawings illustrate portions of the syringe pump housing that form no part of the claimed design.

1 Claim, 5 Drawing Sheets(56)
